UNITED STATES PATENT OFFICE.

FRANK S. VARNEY, OF EASTPORT, MAINE, ASSIGNOR TO BOOTH FISHERIES COMPANY, OF CHICAGO, ILLINOIS, A CORPORATION OF DELAWARE.

PACKING-HOUSE EQUIPMENT.

Application filed November 7, 1924. Serial No. 748,443.

The present invention is related to packing house equipment, and more particularly has to do with such equipment as employed in the packing of fish and similar products.

Its main and primary object is to provide a compact arrangement of the packing tables whereby to promote economy in the floor area for their accommodation, and enable 10 their grouping with respect to each other in such manner as to permit the free working of a maximum force of operatives in a minimum amount of space.

A further object is to provide equipment 15 of the character specified the elements of which are so organized and related as to facilitate access by the operatives to the product to be packed, as well as to the containers for receiving the product. The 20 packing operation thus may be expedited, the operatives being relieved of trips to remote points for procuring additional supplies of the product and the containers in which to pack the same.

Other objects and advantages of the invention will become apparent as the nature 25 of the improvements is better understood, the invention consisting substantially in the novel construction, combination and arrangement of parts hereinafter fully described, illustrated in the accompanying drawings, and finally pointed out in the appended claims.

A practical embodiment of the invention 30 is delineated herein, but this is to be considered from the illustrative standpoint, and not as imposing restriction or limitation upon the invention.

In the drawings,—

Fig. 1 is a plan view illustrating in 35 schematic arrangement the herein described invention;

Fig. 2 is an end view thereof;

Fig. 3 is a side elevation of two of the 40 units in their associated relation with the feed chute for delivery of the containers for receiving the product to be packed;

Fig. 4 is a top plan view, partially in 45 section, of the construction illustrated in Fig. 3.

Referring now in detail to the accompanying drawings, and particularly to Fig. 1, the herein described equipment includes a 50 plurality of units 10 which are aligned with each other across one dimension of a pack-

ing-room or space 11. Preferably, the aligned units 10 are arranged in tiers spaced apart to provide a trucking aisle 12, whereby to permit trucks to pass between the tiers for supplying the units with the material 60 to be packed, and likewise removing the filled containers therefrom, as well as the refuse discarded in connection with the packing operations. A convenient arrangement of this sort contemplates the positioning 65 of the tiers with the units back to back.

Each of the units 10 comprises a table, as clearly illustrated in Figs. 2, 3 and 4, of appropriate construction, the tables in the tiers being spaced apart so that an operative 70 may stand at each side of the table, and two or more operatives be received by the space between a pair of tables. These tables are also arranged in transverse relation to the length of the tier, and extending between 75 adjacent tables is a supporting shelf 13, said shelf serving to join the tables throughout the tier.

Supported by each shelf 13 is a hopper 14, which is substantially rectangular in form 80 and closed at its sides and ends, with the exception of the lower portion of the front side, or that side which faces the space between the contiguous tables 10. At that part of the front side the hopper has a discharge 85 opening 15. This hopper is designed to receive empty cans or similar containers in which the product is to be packed, and being positioned opposite to the working space between a pair of the tables 10, the cans or 90 containers which pass through the discharge opening 15 are immediately available for convenient access by the operatives occupying that space. The front face of the hopper 14 is set back from the extreme front edge of the supporting shelf 13, so that a platform is provided on to which the cans or containers may discharge as they pass out of the opening 15. To prevent the containers passing over such edge, and dropping to the floor, a guard flange 16 surrounds the front edge of the shelf 13, and likewise extends forwardly at the edges of the tables 10 bordering the working space.

These forwardly extending portions of the 95 flange 16 also prevent the product, as the same is deposited on the tables, being displaced from the tables.

That the hoppers 14 may be supplied with 100 containers from time to time each of the 105

- same is provided with an upwardly extending feed chute 17. These chutes are connected with suitable openings in the floor above the floor on which the tables 10 are arranged, as designated by the numeral 18, or this floor may be a loading platform. Each of the chutes preferably is formed of corner supporting posts 19 between which are located foraminous walls 20. The walls 20 may be of open mesh wire fabric or any other suitable material. In the descent of the containers through the chutes 17 they pass into the hoppers 14, and readily may be drawn through the openings 15 of these hoppers, or if the hoppers 15 be filled the containers will pass out of the opening and become deposited on the portion of the shelf 13 immediately in front of the respective hoppers.
- 20 At the ends of each of the hoppers 14 are provided angle iron supporting slides 21 arranged horizontally across such ends. The slides 12 of each hopper co-operate with the slides of the contiguous hoppers to provide means for supporting trays containing the product to be packed. These trays, therefore, occupy the space between the hoppers 14, and each tier of the trays is aligned longitudinally with one of the tables 10. The trays readily may be inserted into the slides 21 from the trucking aisle 12, and as the material contained in the trays is required by the operatives, the trays readily may be removed by the operatives and deposited on the tables 10, thus providing for the operatives a continuing supply of the product, and eliminating necessity for the operatives to leave the tables, pass to remote points to obtain new supplies of the product, and then return to the tables with such supplies.
- Each of the tables 10 also is provided in the top thereof with an opening 22 from which extends an inclined pendent discharge chute 23. The chute 23 and the opening 22 of each table receives the refuse of the product being packed, which refuse is conveyed by the chute 23 to a collecting receptacle 24, such as a box or similar receiver. The discharge point of the chute 23 preferably is directed towards the rear of the table, or towards the trucking aisle 12, so as to deposit the refuse in receptacles which may conveniently be collected by the trucks passing up and down the aisle 12. This relieves the space occupied by the operatives from congestion, and permits the filled receptacles 24 to be removed without interfering with the operatives as they stand at the tables.
- 60 In the use of the herein-described equipment the material to be packed and the containers in which the material is packed are continuously supplied to the operatives. As fast as the trays with the product are removed from the slides 21, additional trays

are introduced to the slides from the aisle 12. The hoppers 14 also are likewise continuously supplied with the containers, and as the latter are removed from the hoppers the containers gravitate through the chutes 17 into the hoppers, the chutes in turn being replenished from the floor above by introduction of the containers into the upper ends of the chutes. The equipment, therefore, provides such an organization of the tables with respect to the supply of the product to be packed and the containers for the same that the operatives are not required to leave their stations at the several tables to procure fresh supplies either of the product or the containers. Furthermore, with the tables arranged in the form of units and grouped in tiers, economy of floor area is obtained, so that the floor space of the packing-room may be utilized to the maximum extent, as well as for the accommodation of the maximum number of employees.

Obviously, the equipment is capable of use for the packing of various products, but, as above indicated, it is primarily intended for the packing of fish and similar commodities, in which industry it has particular advantages because of the chute 23 by which the refuse readily may be conveyed from the surface of the tables 10.

I claim:—

1. Packing house equipment, comprising a plurality of tables arranged in spaced relation to and parallel with each other, supporting shelves connecting said tables at one of their ends, a vertically-disclosed chute arranged above each of said shelves for supplying containers thereto for access to the working space between the tables, and means arranged between said chutes, whereby supplies of the product to be packed may be positioned at the respective tables.

2. Packing house equipment, comprising a plurality of tables arranged in spaced relation to each other, supporting shelves arranged across the ends of said tables, means located with respect to each of said shelves for supplying containers thereto for access to the working space between the tables, and a plurality of tray-supporting devices disposed between the container-supplying means, whereby to support a plurality of trays in alignment with the tables for access to the working space between the tables.

3. Packing house equipment, comprising a plurality of tables arranged in spaced relation to each other, supports arranged across the ends of said tables, open-sided hoppers mounted on said supports and discharging towards the latter for supplying containers to the working space between the tables, and means disposed between said hoppers for positioning at the respective tables supplies of the product to be packed.

4. Packing house equipment, comprising

a plurality of tables, arranged in spaced relation to each other, supports arranged across the ends of said tables, open-sided hoppers mounted on said supports for supplying containers to the working space between the tables, and a plurality of tray-supporting devices associated with the hoppers, the tray-supporting devices at the ends of contiguous hoppers cooperating for the support of a plurality of trays in alignment with the table opposite to the space between said contiguous hoppers.

5. Packing house equipment, comprising a plurality of tables arranged in spaced relation to each other, supports arranged across the ends of said tables, hoppers mounted on said supports for supplying containers to the working space between the tables, chutes connected to said hoppers for feeding containers thereto, and means associated with the hoppers for positioning at the respective tables supplies of the product to be packed.

6. Packing house equipment, comprising a plurality of tables arranged in spaced relation to each other, supports arranged across the ends of said tables, hoppers mounted on said supports for supplying containers to the working space between the tables, chutes connected to said hoppers for feeding containers thereto, and a plurality of tray supporting devices associated with the hoppers, the tray supporting devices at the ends of contiguous hoppers co-operating for the support of a plurality of trays in alignment with the table opposite to the space between said contiguous hoppers.

7. Packing house equipment, comprising a plurality of tables arranged in spaced relation to each other, supports arranged across the ends of said tables, means located with respect to each of said supports for supplying containers thereto for access to the work-

ing space between the tables, means disposed between said container-supplying means for positioning at the respective tables supplies 45 of the product to be packed, and means associated with each table for conveying therefrom the refuse incidental to the packing operations.

8. Packing house equipment, comprising a 50 plurality of parallel tables arranged in spaced relation, supporting shelves arranged across said tables at one of their ends, a hopper supported by each of said tables and provided with an open side discharging 55 towards the tables, a vertically-disposed chute projecting upwardly from each of said hoppers and in communication therewith for supplying the hopper with containers from an elevated point, and means disposed between 60 said hoppers and opposite said tables for positioning at the respective tables supplies of the product to be packed.

9. Packing house equipment, comprising a 65 plurality of parallel tables arranged in spaced relation, supporting shelves arranged across said tables at one of their ends, a hopper supported by each of said shelves and provided with an open side discharging 70 towards the tables, a vertically-disposed chute projecting upwardly from each of said hoppers and in communication therewith for supplying the hoppers with containers from an elevated point, and a plurality of tray-supporting devices disposed between the 75 hoppers, the tray-supporting devices at the ends of contiguous hoppers co-operating for the support of a plurality of trays in alignment with the table opposite to the space between said contiguous hoppers. 80

In testimony whereof I have hereunto signed my name.

FRANK S. VARNEY.
